(57) **CLAIM**

The ornamental design for a combined container and ink tanks for a printer, as shown and described.

DESCRIPTION

FIG. 1 is a top, front and right side perspective view of a combined container and ink tanks for a printer showing our new design;

FIG. 2 is a bottom, rear and left side perspective view thereof;

FIG. 3 is a front view thereof;

FIG. 4 is a rear view thereof;

FIG. 5 is a top plan view thereof;

FIG. 6 is a bottom plan view thereof;

FIG. 7 is a right side elevational view thereof;

FIG. 8 is a left side elevational view thereof;

FIG. 9 is a right side elevational view showing the article attached to a printer; and,

FIG. 10 is a rear, top and right side perspective view showing the article attached to a printer with the top cover in an open position.

The broken lines are shown for illustrative purposes only and form no part of the claimed design.
